FUSIBLE CONNECTOR

Clydis J. Patton, Decatur, Ill., assignor to James R. Kearney Corporation, St. Louis, Mo., a corporation of Missouri

Application June 14, 1947, Serial No. 754,716

5 Claims. (Cl. 200—133)

1

This invention relates to fusible connectors for electrical wires. Without limitation thereto, it has more particularly to do with such devices for outdoor use in the operatively connecting of electric distribution lines with feeder output lines from the source. It is designed more particularly to fuse user lines of comparatively low voltage, say 110 to 220 volts, but, of course, the invention is adaptable for use on higher voltage lines.

Primarily and more generally, the invention is used on the low voltage side of a distribution transformer handling, for example, such as high voltage of from 2300 to 6900 volts intake and reducing the same therein down to 110 to 220 volts output.

In cases where two or more user supply lines are connected to the low voltage output side of the transformer by devices of the present invention, it is possible and even probable that only the fusible connection with one line at a time will blow out. Thus, loss of the entire load on the transformer is prevented should a short circuit and blowout occur between only one phase of the low voltage side of the transformer and the place of use or the ground. However, if the fusible connections between the transformer and all of the user lines should blow out at the same time, the length of time the lines may be out of use is minimized because one of the objects of the invention is to facilitate ease and rapidity of fuse replacement in the blowout connection or connections with the least possible time consumed and expense entailed.

There are several types of connectors on the market and in use in the activities covering large areas throughout the country, and with these devices the breaking of electric utility lines and the resultant loss of power while repairs are being made, has long been a troublesome and expensive problem for power and light companies, to say nothing as to the inconvenience and loss to the user. Also, corrosion and decay have long been the cause of expensive parts repairs and full replacements, as the usual types of connectors are made of such material and in such combinations and assemblies of parts that, due to the same being constantly exposed and subject to the ravages of the elements, it is often difficult and in some cases quite impossible to get the assemblies apart and detached from the wiring, even for full replacement, to say nothing of the impossibility of parts repair or replacement. This is especially true where the parts of the assembly are entirely of metal and consist of bolts, nuts, screws and other threaded or specially

2

and tightly interfitted or interlocked pieces, and the same become so fastened in place that they are broken or marred in removal and it becomes necessary to retap the threaded portions or reform or refinish other portions. Frequently, the entire assembly has to be replaced, while, on the other hand, the screw-threaded and certain other interlocked parts become loose as a result of vibration, changes in temperature, etc.

10 A further object of the invention is to produce an improved fusible connector device which is especially practical and efficient for outdoor use and will avoid the disadvantages just above pointed out, is easily and economically manufactured, and from ordinary use and effect of the elements usually requires only the replacement of the blow-out fuse member of the assembly.

Other objects and advantages to be attained will hereinafter more fully appear in the following description.

Generally stated, the improved device of the present invention includes a housing body and cooperative, movable, exterior parts of electrically non-conductive and insulative material, preferably a plastic or other non-metallic substance of high tensile strength and resistant to effects of exposure to the elements and to the extreme temperatures of summer and winter. The only exposed metallic member is a coil spring which surrounds a portion of the housing body and normally urges the other external movable members apart so as to hold said parts in retentive engagement respectively with a user line wire and a feeder wire, and with the so engaged wires respectively in retentive engagement with a removable and replaceable fuse element located and yieldably retained longitudinally positioned within the housing body.

40 The invention further consists in the peculiar form and arrangement of the fuse element itself and in its particular mounting in the housing body and the especial cooperative relation thereto of the exterior parts of the device.

45 In the accompanying drawings illustrative of a practical but non-limiting exemplification of the invention,

Figure 1 is a side elevation of the body housing or fuse holder;

50 Figure 2 is an elevation of one end of said housing;

Figure 3 is an elevation of the opposite end of the housing;

55 Figure 4 is a perspective view of the housing looking from below;

Figure 5 is a bottom plan view of the housing; Figure 6 is a longitudinal sectional view of the external longitudinally movable thimble member;

Figure 7 is a perspective view of said thimble member;

Figure 8 is a longitudinal sectional view of the external sleeve member which cooperates opposingly to the thimble member on the housing body;

Figure 9 is a perspective view of said sleeve member;

Figure 10 is a side elevational view of the thimble and sleeve urging spring detached;

Figure 11 is a longitudinal sectional view of the complete device assembled and in normal holding engagement with the user line wire and the feeder wire;

Figure 12 is a view somewhat similar to Figure 11, but with the fuse proper indicated as blown and the movable parts and attached wires moved resultantly to a different position;

Figure 13 is a longitudinal section of the complete device assembly but with the sleeve member moved further into the thimble member than shown in Figure 11 for the act of moving the user line wire into or removing it from the correlated retainer notch of the complementary fuse body member within the housing body;

Figure 14 is a perspective view of one of the fuse body members detached;

Figure 15 is a similar view of the companion fuse body member;

Figure 16 is a side elevation of the fuse body member shown in Figure 14 but on an enlarged scale;

Figure 17 is a cross-section taken on or about the line 17—17 of Figure 16;

Figure 18 is a fragmentary view, partly in section taken on or about the line 18—18 of Figure 16; and

Figure 19 is a schematic view illustrative of a practical adaptation and use of the present invention.

Referring now to the drawings in detail and first more particularly to Figure 19, the numeral 1 designates an electric service line pole having a cross-tree 2 thereon, from which latter is suspended a conventional transformer 3. The transformer may be of any approved interior form and arrangement. Hence, the interior parts are not shown.

Leading into the transformer 3 from any source of high voltage current (not shown) is a feed wire 4, while a conventional ground wire 5 leads from the transformer.

By way of example, the high voltage in the intake wire 4 of the transformer, in the usual and more common practice, will be from 2300 to 6900 volts. The output voltage from the transformer, in the more common practice, will be much lower than that of the transformer intake, say from 110 to 220 volts.

In the illustration in Figure 19, there are shown two separate user line or distribution wires 6 and a single ground wire 7. The two user line wires 6 and single ground wire 7 are supported from the pole 1 by conventional insulated brackets 8. The details of the brackets 8 being obvious and well known, such details are not shown in the drawings.

The ground wire 7 is permanently connected, as by the wire 9, to the transformer 3 in an obvious and well known manner. That is to say, the connection 9, externally of the transformer 3, is merely shown conventionally, and

it is deemed unnecessary to show any interior grounding provisions of the transformer.

In the illustration in Figure 19, conventional low voltage output wires 10 are indicated as leading from the transformer 3, and the same are attached at their outer ends respectively to the user line wires 6 by fusible connectors 11, the details of which latter constitute a part of the essence of the present invention. That is to say, the construction, arrangement and particular application of these connectors 11 constitute essential and important features of the invention. Hence, the same are fully shown in Figures 1 through 18, and accordingly described.

The full connector assembly 11 is shown in detail in Figures 11, 12 and 13. The several parts are shown individually in Figures 1 through 10, and in Figures 14 through 18.

Referring first specifically to Figures 1 through 5, the numeral 12 designates a main housing body or holder for a removable and replaceable fuse element proper. As shown, this member 12 is generally cylindrical throughout, that is, externally and except for a mutilated flange 13 located externally and near one end thereof.

Extending longitudinally from end to end of the housing body 12 is an axial cored passage or slideway 14. This passage or slideway 14 is rectangular in cross-section and is of one size in cross dimensions, except at one end of the housing body, that is, the end adjacent the external mutilated flange 13, where the passage or slideway is counter enlarged or recessed, as at 15.

Near the end of the housing body 12 remote from the recessed passageway or slideway end 15, the housing body is provided with diametrically opposite longitudinal slots 16 in its sides, said slots communicating with said passage or slideway 14 and thereby providing a substantially elongated longitudinal passage which is normally open throughout a part of its length fully cross-wise of the housing body.

Adjacent the external mutilated flange 13, the housing body 12 is cutaway throughout considerable area from its underside so as to produce an appreciably large notch or recess 17 having one wall, remote from the flange 13, as at 18, formed flat faced throughout and disposed at right angles to the longitudinal axis of the housing body 12. The opposite side wall of the recess or notch 17, near the flange 13, is cut out curvily, as at 19 (see Figure 1). As to this side wall notched or curved recess portion 19, it is here noted that as far as the present invention is concerned, the same may be varied in size, and, in some cases, even eliminated entirely, if the first described notched or recessed portion 17 is formed of a width from side wall to side wall considerably greater than the diameter of a user line wire 6, which latter, as hereinafter described, is moved laterally of itself into or out of said notch or recess 17 as the wire is attached to or removed from the fusible connector 11.

Preferably, in some forms of the adopted housing body 12, the same may be further recessed on its underside, as at 20, to afford a provision for easily and more readily guiding the applied line wire 6 into the aforesaid notch or recess 17.

Fitted longitudinally slidably on the housing body 12 is a sleeve member 21 having an internal lug 22 to fit slidably in a longitudinal groove 23 formed in the underside of the member 12 (see Figures 4 and 5). Also fitted longitudinally slidable on the housing body 12 is a thimble member

24 having an interior diameter somewhat larger than the exterior diameter of the sleeve member 21 or at least large enough to permit the sleeve member to be slid into said thimble member 24 (see Figures 11 and 13).

The thimble member 24 is formed with an internal annular shoulder or collar portion 25 which is of an interior diameter to fit longitudinally slidable on the housing body 12, and this shoulder or collar 25 is provided with a lug 26 which, like 10 the lug 22 on the sleeve member 21, fits longitudinally slidable in the longitudinal groove 23 of the housing body 12.

The outer end of the groove 23, or, in other words, the end remote from the recessed or 15 notched portion 17 (see Figure 5) is closed, as at 27, so as to afford a stop to prevent unintentional removal of the members 21 and 24 from the housing body. However, to permit the placing of the members 21 and 24 on the housing body, and the 20 intentional removal of the same, at will, a laterally offset, open-ended, relatively short groove 28 is provided adjacent this closed end of the groove 23, communicably therewith and with a bayonet effect. That is to say, to place the members 21 and 24 on the housing body 12 it is only necessary to first slide the members 21 and 24 on with their lugs 22 or 26, as the case may be, in said short groove 28 until the lug reaches the place of lateral communication between the grooves 23 and 28, 30 and then turn the member 21 or 24, as the case may be, to move its lug into the groove 23, whence the applied member is slidable longitudinally on the housing member but held from rotation thereon. Obviously, by a reverse action, the member 21 or 24, as the case may be, is as readily removed.

In accordance with the present invention the said parts 12, 21 and 24 are preferably made of a plastic material of high tensile strength and of electric non-conductivity, or the same may be made of any other suitable material.

A coiled spring 29, of course, of metal but of non-corrosive character, is sleeved on the housing body 12 and interposed under compression between the applied sleeve member 21 and the applied thimble member 24. This spring 29 is of a length and forceful strength so that when applied in use, it reacts lengthwise so as to force the sleeve member 21 towards and against the flange or collar 13 of the housing body 12 and the thimble member 24 with its lug 26 against the end wall 27 of the groove 23. That is to say, this is what happens when the members 21 and 24 and the spring element 29 are thus placed on the housing body 12 before the special fuse members are placed as a complete assembly within the cored axial passage or slideway 14 of the housing body 12, as will now be described.

The fuse assembly proper comprises one electrically conductive metallic member 30 and a separate but cooperative companion member 31 of like material. Both of these members are slightly elongated and rectangular in cross section so as to fit slidably in the longitudinal passage or slideway 14 of the housing body, and they are substantially identical in form and size except being arranged in a reverse order. That is to say, the inner ends of the members 30 and 31, although in reverse arrangement, are rabbetted, as at 32, and the reduced body ends are grooved longitudinally on opposite sides, as at 33. These side grooves 33 are cross-connected by a transverse hole 34.

The members 30 and 31 are each further pro-

vided with an inclined notch 35, each notch 35 being of a diameter to receive freely therein either a line wire 6 or one of the output wires 10 of the transformer 3 when the connector 11 is applied in use as indicated schematically in Figure 19 and as shown in detail in Figures 11, 12 and 13.

Normally, the metallic members 30 and 31 of the fuse assembly proper are coupled together in a definitely spaced relation by an actual fusible member 36 which is seated at its ends on the rabbetted inner end portions 32 of said fuse body members 30 and 31 and there soldered in place, these parts as thus assembled constituting an integral fuse unit.

Inasmuch as the actual fuse member 36 is necessarily of comparatively soft metal and obviously lacking in the required tensile strength to assuredly hold the body members 30 and 31 normally in their spaced connected relation, a supplemental tie wire 37 is attached at its ends in the side grooves 33 and cross aperture 34 of the respective body members 30, 31 of the fuse assembly proper and there soldered in place. This tie wire 37 is of greater tensile strength but of much smaller gauge than the actual fuse element 36, which latter, of course, is the part to usually blow out first under excess voltage load. However, the tie wire 37, designed to more assuredly hold the body members 30 and 31 normally in their coupled relation, is located in close parallel relation to said actual fuse element 36. Thus, the flash of fire occurring as said member 36 blows, burns and breaks the tie wire 37. The parts 30 and 31 are then disconnected and movable farther apart as indicated in Figure 12 as compared to their connected relation as shown in Figures 11 and 13, the separating movement of said parts 30 and 31 being effected by the reaction of the normally compressed spring element 29.

It is here noted that the fuse body member 30 has a flanged head 38 at its outer end. This head 38 enters the end recess 15 of the longitudinal passage or slideway 14 of the housing body 12 and bears against the shoulder provided at the bottom of said recess 15 with limiting stop effect when the fuse unit is inserted in housing body 12 as shown in Figures 11 and 13. It is here further noted that, normally, in the proportioned 60 fuse assembly, the distance from the flanged head 38 is such that the notch 35 in the fuse body member 31 is brought contiguous to the transverse plane of the inner ends of the side slots 16 of the housing body 12 when the flanged head 55 38 is seated in the end recess 15 of the housing body. At this time, too, the notch 35 of the fuse body member 30 is in registration with the recess 17 of the housing body. By this proportional arrangement of the parts, and the wires 6 and 10 60 in place as shown in Figure 11, the pressure of the sleeve 21 and thimble 24, under the influence of the spring elements 29, against the engaged wires 6 and 10, holds the wires securely against the outer wall portions of the notches 35 in the 65 fuse members 30 and 31. Moreover, with the parts thus engaged (see Figure 11) and the wire 10 being contiguous to the inner ends of the housing body side slots 16, only very limited, if any, movement of the fuse assembly is permitted 70 in one direction longitudinally of the housing body, while the flanged head 38 prevents any appreciable movement of the fuse assembly in the opposite direction.

Obviously, by reference to Figure 11, it is seen that the spring-urged sleeve member 21 and

thimble member not only hold the wires 6 and 10 in retentive engagement with the notches 35 of the fuse members 30 and 31 but the fuse unit is retained in the housing body 12. It is further noted, by reference to Figure 12, that the disconnected fuse members 30 and 31 are also retained in the housing body 12 after the actual fuse element 36 is blown and the tie wire 37 is broken.

In order to hold the connected wires 6 and 10 more securely in place, the sleeve member 21 is provided at one end with diametrically opposite notches 39 and the thimble member 24 with like notches 40 to engage over the wires.

As hereinbefore pointed out, with the fuse assembly removed from the housing body, the cooperatively assembled exterior parts including the sleeve member 21, the thimble member 24 and the interposed spring element 29, are retained on the housing body 12 by the flanged collar 13 and the groove end wall 27. To apply the feeder wire 10 it is only necessary to slide the thimble member 24 back against the spring 29, compressing the latter, and inserting the end portion of the wire 10 laterally through one of the side slots 16 of the housing body and through the registered notch 35 of the member 31 of the fuse assembly as previously inserted in the housing body, and then releasing the thimble member 24 to the reactive effect of the spring element 29. At this time, the sleeve member 21 is pressed by the spring element 29 against the external flanged collar 13. This particular position of the sleeve member 21 is not shown in the drawings but the thimble member 24 and the wire 10 will be in the engaged relation shown in Figures 11 and 13. Then, to apply the line wire 6, the sleeve member 21 is retracted and held, compressing the spring element 29 as indicated in Figure 13, so that the line wire 10 can be moved into the housing body notch 17 and the registered notch 35 of the member 30 of the fuse assembly. The sleeve element is then released to the reaction of the spring element 29 and the wire 10 and associated parts will be in the relation indicated in Figure 11. The wires 6 and 10 can be released from their retentive engagement with the fuse parts 30 and 31 by a similar retractive actuation of the sleeve member 21 and thimble member 24.

It is here further pointed out that with the actual fuse member 36 blown and the tie wire 37 broken as indicated in Figure 12, the spring element 29, under reactive effect, may have become extended to a length such that the wire 10 would be moved to a position where it is closely contiguous to or actually in contact with the outer end of the side slot 16 of the housing body. Thus, if the extended spring element be of a certain length, as indicated in Figure 12, the outer end of the sleeve member 21 may be in or about the position shown, that is to say, the outer end of the sleeve member may be spaced some distance from the external flange collar 13. In this position of the sleeve member 21 the wire 6 is still engaged in the notches 39 of the sleeve member. However, if the spring element 29 be extensible to a greater length than that shown in Figure 12, with the actual fuse 36 and tie wire 37 broken as shown, then the sleeve member 21 will be moved by the spring element into contact with the external flanged collar 13, in which position of the sleeve member 21, of course, the fuse body member 30 will be moved correspondingly some distance outwardly from the position shown in Figure 12, that is to say, provided, of course, that the notched wall enlargement 19 is

provided at the outer side of the recess 17 of the housing body. However, if the wall notch 19 is not provided as shown, and the outer wall of the recess 17 is spaced inwardly some distance from said external flanged collar 13, the sleeve member 21 obviously will not be moved into direct contact with the flanged collar 13 if the wire 6 is not removed from engagement with the fuse member notch 35 and the notches 39 of the sleeve member 21.

From the illustration in the drawings and the foregoing description, it is obvious that a fusible connector is produced for the purpose described, of which device the housing body and cooperative external parts can be used over and over again, and that the actual fuse unit assembly is readily placed originally in, removed from and replaced in the housing body at the location, thus not only at minimum expense to the power and light company but also to the advantage of the user, service to whom can be restored rather expeditiously after a fuse blowout on the supply line. The connector device of the present invention is further of material advantage in that it is especially adaptable practically and efficiently for use where a transformer receiving very high voltage and reducing the same to the ordinary commercial relatively low voltage has its output connected to two or more separate distribution lines. In such cases, it is obvious that, usually, only one fusible connector will blow out at one time, so that only the one user or group of users served by that particular line will be temporarily without service and that service may be quickly restored should a fuse blowout occur.

It is further noted that the connector device of the present invention is constructed to withstand the effects of the elements in all seasons of the year as well as the extreme heat of summer and cold of winter.

The illustrated disclosure is but one practical exemplification, and modification and change is contemplated within the purview of the invention as defined in the appended claims. The invention, therefore, is not limited to the specific construction and arrangement shown.

What is claimed is:

1. A fusible connector of the character described, the same comprising an elongated housing body of electrically non-conductive material, said body having cooperatively opposed external members mounted longitudinally movable thereon with a spring element interposed between and urging said cooperatively opposed external members in a direction away from each other, and a removable and replaceable fuse unit assembly in said housing body, said fuse unit assembly comprising two opposed separate longitudinal electrically conductive members normally connected in spaced relation and in longitudinal alignment by an actual fuse member, said housing body adjacent one end having an opening to receive transversely of the body a delivery line wire and adjacent its other end an opening to receive a distribution line wire, the opposed fuse assembly members having wire receiving openings therein, and the spring-urged external cooperative members on said housing body, under the influence of said spring element, bearing retentively on the wires received in said receiving openings in said fuse assembly members.
2. A fusible connector device as set forth in claim 1, wherein, in addition to the actual fuse member connecting the longitudinally aligned and spaced-apart fuse assembly members, a sup-

plemental tie wire, paralleling and in close relation to said actual fuse member, also connects said fuse assembly members, said tie wire becoming broken and ineffective as a tie element upon and by the blowing of said actual fuse member.

3. A fusible connector of the character described, comprising an elongated generally cylindrical housing body of electric non-conductive material, said body housing having a central longitudinal slideway therein and extending from end to end thereof, one end portion of the slideway being counter-enlarged, and the housing body having lateral openings to the outside and communicable internally with said longitudinal slideway of the housing body, opposed external cooperative members mounted longitudinally slidable on the housing body, an interposed spring element normally urging said external members away from each other and one towards each end of the housing body, means for limiting such movement of the external members and retaining them on the housing body, a removable and replaceable fuse unit assembly comprising two opposed, spaced apart and longitudinally aligned electrically conductive body members connected together as a unit by an actual fuse member, said fuse body members having openings to receive retentively and respectively a feed wire and a distribution line wire, one of the fuse body members having a headed enlargement at its outer end to enter said end enlargement of the central longitudinal slideway of the housing body when the fuse unit assembly is inserted into said slideway, so that, when the fuse unit assembly is placed and in limited position in the housing body, the wire-receiving openings of the fuse body members are located in position to receive the wires, said spring element, in its reactive effect, normally urging said external cooperative members on the housing body into retentive engagement with the wires as engaged by the fuse body members.

4. A fusible connector device as set forth in claim 3, wherein, in addition to the two fuse body members being connected normally by the actual fuse member, said fuse body members are also connected by a supplemental tie wire paralleling

said actual fuse member and relatively close thereto whereby said tie wire becomes broken upon and by the blowing of the actual fuse member.

5. The hereindescribed characteristic fusible connector device, comprising an electrically non-conductive housing body having longitudinally slideable externally thereon two opposed cooperative members normally spring-urged away from each other and towards the respective ends of the housing body, said housing body having an axial slideway therein and extending from end to end thereof, and also having a lateral opening adjacent each end and each opening being in communication with said axial slideway of the housing body, and a fuse unit assembly to be placed removably and replaceably in said slideway of the housing body with provision for limiting the inserting movement of the fuse unit assembly, said assembly comprising a longitudinally spaced-apart pair of electrically conductive fuse body members normally connected together by an actual fuse member, each fuse body member having a wire-receiving and retaining opening positionable registrably with respect to the lateral openings of the housing body, and said spring-urged external cooperative members on the housing body having provision at their outer ends for retentive engagement respectively with an applied feeder wire and an applied user line wire, said wires being moved laterally into the housing body through its aforesaid lateral openings and received into said retaining openings of the fuse unit body members and being held in place by said spring-urged external cooperative members.
